BODY TREATING TABLE

William P. Smith, Los Angeles, Calif., assignor of
one-half to Raymond Addison Evans, Los Angeles, Calif.

Application June 10, 1931. Serial No. 543,370

18 Claims. (Cl. 128—70)

My present invention relates to a body treating table of the type illustrated in my patent application 515,564 filed April 13, 1931.

A particular object and feature of the present invention is to reciprocate the table part of the structure on which the patient lies while the arm to which the feet, arms, or head, are connected, is oscillated, the object being to obtain an oscillating movement of the lower or upper extremities of the body, this giving a bending action quite frequently employed in osteopathic and chiropractic treatments.

In my present invention the supporting table or bed on which the patient rests is reciprocated in synchronism with the oscillating movement of the arm so that if the feet or arms are connected to the arm that undue strains will not be exerted on the body but the patient may rest comfortably and substantially only experience the movement caused by the oscillating arm. The reciprocation of the table or bed is arranged so that when the arm is in its lowermost position the bed is advanced toward the arm and when the arm is elevated the bed is retracted.

A further detail object and feature of my invention is varying the reciprocating movement of the bed in accordance with a circular oscillation of the arm so that for the slight oscillation the bed will only have a slight reciprocating movement but for the large or the maximum oscillation the reciprocation of the table will be commensurate therewith, these various motions being combined so that there is substantially a constant distance from the body clamp on the bed to the tension bracket on the arm; this constant radius preventing undue strain being brought to bear on any part of the body of the patient, which is held relatively stationary by the body clamps on the bed.

Another detailed feature in connection with the reciprocating bed is the manner of mounting this to obtain the reciprocation.

My invention is illustrated in connection with the accompanying drawing, in which:

Fig. 1 is a side elevation partly broken away of the table, showing the arm in its lowermost position;

Fig. 2 is a similar view showing the table structure in section with the arm in its most elevated position;

Fig. 3 is a detailed longitudinal section with parts broken away illustrating the operation of the reciprocating bed.

In this construction I employ a cabinet 11 somewhat similar to that of my former construc-

tion. In this construction a driving mechanism 12 is of the same type as in my former patent application and operates the arm 13 which has a universally jointed connection 14 with a screw 15 mounted on the frame 16 which frame is secured to the drive shaft 17. The arm 13 is pivoted by a pivot pin 18 in the rock shaft 19 and as the universally jointed end 14 swings in a circle it rocks the rock shaft 19. The frame 16 and the screw 15 are the same as in my copending application Serial No. 515,564.

An arm 20, preferably formed tubular, is pivoted on pivot pin 18 to the rock shaft 19 and is firmly connected to the end 21 of the arm 13 adjacent the pivot 18. Hence, as the arm 13 oscillates, the extension arm 20 also oscillates, these both having a circular oscillation. The horizontal rock shaft 19 has pivot axles 19' at each end, each axle being pivoted in a lug 50' at opposite sides of the opening 50 (note 75 Figure 3). This forms a horizontal hinge or pivot for the rock shaft 19 and the pin 18 extending therethrough may be considered as a vertical pivot. As the arm 20 is rigidly connected to the arm 13, and this latter pivoted 80 on the vertical pivot bolt 19, hence as the arm 13 is given an orbital movement having horizontal and vertical components, it communicates an orbital movement to the arm 20.

In my present application the arm 20 is not 85 extensible and has no telescopic or sliding movement of the different parts. A pad 22 is secured to this arm by clamping straps 23 and such pad overlaps a flat plate 24 which is attached to the rock shaft 19, this plate being substantially of 90 the same type as illustrated in my former patent application. A tension bracket designated generally at 25 is secured to the outer portion of the arm 20, this being slidable, and is of substantially the same construction and function as 95 in my former patent application.

A reciprocating bed 26 employs longitudinal tracks 27 on the bottom, these tracks bearing and operating on rollers 28, such rollers being journaled in the upper part of the cabinet structure. 100 The bed has a suitable pad 29. This pad has a longitudinal slot 30 below which is a tension screw 31, this screw having a crank 32 at the outer end and a bearing 33 at the inner end. The tension post 34 is connected to the screw in the 105 same manner as in my former patent application by means of a nut 35.

The body clamp 36 employs a horizontal pad 37 with two clamping jaws 38, these being arranged to clamp a portion of the patient's body 110

on the bed in the same manner as in my previous application.

The mechanism for reciprocating the bed utilizes a rack 39 secured on the under side of the bed below the body clamp 36. Meshing with this there is a segmental gear 40 which is mounted on an oscillating arm 41, this being pivoted at 42 with a frame structure 43 built into the cabinet. This oscillating arm has a series of perforations 44 for adjustment, and connected in one of these there is a link 45, this arm being connected to a lever 46 which is firmly connected to the rock shaft 19. Therefore, on rocking movement of this rock shaft the oscillating arm 41 is actuated in a vertical plane and, hence, reciprocates the bed 26, and this rock shaft is rocked by the oscillating arm 13 having the extension 20. It will, therefore, be seen that as this latter arm and its extension are oscillated in a circular manner 20 that the table has a reciprocating motion.

The degree of the circular oscillating motion of the arm 20 is regulated in the same manner as in my prior application in which it may be seen that this may be from a small oscillation to a 25 large oscillation, and as the oscillation increases in extent, manifestly, the rock arm 19 has a greater degree of rocking motion and this, through the medium of the segmental gear 40, reciprocates the bed varying degrees. In addition, when 30 desired, the link 45 may be adjusted on the arm 41 to give a greater or a less relative motion of the bed and the oscillating arm 20.

The oscillating arm 20 is counterbalanced by means of having a counterbalance arm 47 which 35 is secured to the rock shaft 19, this having a counterbalance weight 48 on the end. Thus, in the circular oscillating movement, the counterweight arm and the counterweight only have a vertical oscillating movement. In this construction I 40 place the counterweight above the arm 13.

Another feature of this design over my former application is that end 49 may be substantially closed except for the relatively small opening 50 at the top to allow passage of the lever 46 and 45 the link 45.

The manner of using my body treating table is substantially as follows:

Presuming that the hips and the legs of the patient are to be given the oscillating treatment, 50 the patient lies on the table so that the body clamp 36 may be clamped at substantially the hips. The feet are connected to a harness and attached to the tension bracket 25. The hands are also engaged in a holding device, which latter 55 is secured to the tension post 34. Both the tension bracket 25 and the tension post 34 may be adjusted longitudinally of the arm and of the bed, respectively, and, hence, increase or decrease the pull or tension on the body of the patient, 60 and as the pad 37 with the whole of the table top reciprocates this prevents an undue strain being brought on any part of the body. The machine is arranged, manifestly, so that the patient may have the feet clamped to the tension post 34 and the arms secured to the tension bracket 25, and thus give a movement to the upper part 65 of the body, the body clamp 36 being adjusted to the portion of the body which it is desired to hold relatively stationary.

Various changes may be made in the details of construction without departing from the spirit or scope of the invention as defined by the appended claims.

I claim:

1. In a body treating table, the combination

of an oscillating arm, a reciprocating bed, and means to interconnect the arm and the bed for relative reciprocating movement of the bed and oscillation of the arm.

2. In a body treating table, the combination of 80 an oscillating arm having a somewhat circular motion considered transversely of the arm, a reciprocating bed, and means to interconnect the arm and the bed to regulate the reciprocating motion of the bed in conformity with the degree 85 of oscillation of the arm.

3. In a body treating table, the combination 90 of an oscillating arm, a reciprocating table, means to interconnect the arm and the table to reciprocate the table in synchronism with the oscillation of the arm, and means to vary the amount of oscillation of the arm and reciprocation of the table.

4. In a body treating table, the combination 95 of an oscillating arm having an orbital motion considered transversely of such arm, a reciprocating table, an interconnecting means between the table and the arm to reciprocate the table in synchronism with the oscillation of the arm.

5. In a body treating table as claimed in claim 100 4, means to vary the oscillation of the arm to increase or decrease its orbital motion, the means interconnecting the bed with the arm varying the reciprocation of the bed in conformity with the changes of oscillation of the arm.

6. In a body treating table, the combination 105 of a rock shaft, a vertically oscillating arm connected thereto to rock with said shaft, a bed having a reciprocating portion positioned above said shaft, interconnecting means between the arm and the bed to reciprocate the bed during the oscillation of said arm and the rocking of said shaft.

7. In a body treating table as claimed in claim 115 6, means to convey a lateral oscillation to the arm in combination with the vertical oscillation and thereby impart to the arm an orbital movement considered transversely, the interconnecting means between the arm and the table moving the table forwardly toward the arm when the 120 arm is in its lowermost position and moving it in a reverse direction away from the arm when the arm is in its uppermost position.

8. In a body treating table, the combination 125 of a horizontal rock shaft, an arm pivotally connected thereto, means to rock said shaft, and means to oscillate the arm on its pivot and thereby communicate to such arm an orbital movement considered transversely, a slidably bed having one end positioned above the rock shaft, 130 means to interconnect the bed and the rock shaft to reciprocate said bed on the rocking of said shaft.

9. In a body treating table as claimed in claim 8, the means connecting the bed and the rock shaft 135 including a rack connected to the bed, an oscillating segment geared therewith, and a connection between the rock shaft and said segment.

10. In a body treating table, the combination 140 of a horizontal rock shaft, an arm pivotally connected thereto, means to rock said shaft and to pivot the arm on its pivot, the rocking motion of the shaft and pivoting of the arm being combined to convey to the arm an orbital movement considered transversely, a slidably mounted bed, 145 a rack connected to the bed, an oscillating segment having an oscillating arm connected therewith, a link connected to the arm, and a lever interconnecting the link and the rock shaft.

11. In a body treating table, the combination 150

- of an oscillating arm having a tension bracket connected thereto, a slideable bed having a body clamp and a tension post, said bracket and post being adapted for attachment of the legs and the 5 arms of a patient, and means to oscillate the arm and to reciprocate the bed in synchronism. 80
12. In a body treating table, the combination of an oscillating arm mounted to oscillate between lower and upper extremes of movement, a reciprocating bed, a tension bracket on the arm and a tension post on the bed adapted for attachment to the legs and arms of a patient, and means to synchronize the oscillation of the arm and reciprocation of the bed whereby when the arm is in its 10 lowermost position the bed is drawn forward toward the arm and when the arm is raised the bed is removed further from the arm. 85
13. In a body treating table as claimed in claim 12, the means for oscillating the arm having in addition a means to convey a lateral motion to the arm and thereby operate the arm in an orbital movement considered transversely of such arm. 90
14. In a body treating table, the combination of a rock shaft, an arm pivotally connected thereto, means to rock the shaft and to oscillate the arm on its pivot whereby the combination of movements operates the arm in an orbital movement considered transversely, a slideably mounted bed having a body clamp, the arm having a tension bracket and the bed having a tension post for attachment to the legs and arms of a patient, means to synchronize the oscillation of the arm and the reciprocation of the bed to move the bed 15 forward toward said shaft when the arm is in the lower part of its orbit and to move the bed a further distance from the rock shaft when the arm is in the upper part of its orbit. 100
15. In a body treating table, the combination of a cabinet having a power motor therein, a rock 45 shaft, an extension arm pivotally connected to the rock shaft, said arm having a portion thereof in the cabinet and connected to a drive mechanism operated by the motor to move the arm in an oscillating movement considered transversely, such movement rocking said rock shaft, a bed slideably mounted on the cabinet and having a body clamp and an adjustable tension post, the extension arm having an adjustable tension bracket, said bracket and post being adapted for attachment of the legs and arms of a patient, a rock lever connected to the rock shaft, a link connected to said lever, an oscillating arm connected to the link and having a segmental gear thereon, and a rack on the bed meshing with said gear. 105
16. In a body treating table, the combination of a cabinet, an arm, means to move said arm in an orbital movement considered transversely, a pad on the arm rigidly secured thereto, a reciprocating bed having a body clamp, means for adjustably securing the arms and legs of a patient to the bed and the arm, and means to interconnect the arm and the bed to reciprocate the bed in synchronism with the orbital movement of the arm. 110
17. In a body treating table a cabinet, a bed reciprocatingly mounted thereon, a rack connected to the bed, an oscillating segment meshing with the rack, and an electric motor in the cabinet 50 having a connection to oscillate the said segment. 115
18. In a body treating table a cabinet, a bed reciprocatingly mounted thereon, said bed having brackets mounted on rollers, the under side of the bed having a rack, a pivotally mounted segmental gear meshing with said rack, a tilting and oscillating arm, and a motor in the cabinet forming a drive connection both for the tilting and oscillating arm and for the pivoted segment. 120
